Primary Examiner — Mary Ann Calabrese(74) *Attorney, Agent, or Firm* — Crowell & Moring LLP(57) **CLAIM**

The ornamental design for an electronic display device, as shown and described.

DESCRIPTION

FIG. 1 is a top, front, left side perspective view of an electronic display device showing our new design;

FIG. 2 is a front view thereof, the rear view thereof being identical;

FIG. 3 is a top view thereof; and,

FIG. 4 is a left side view thereof, the right side view thereof being identical.

The broken lines illustrate environmental structure and form no part of the claimed design. The diagonal shade lines illustrate transparency and not surface ornamentation. The horizontal shade lines illustrate contour and not surface ornamentation.
